UNITED STATES PATENT OFFICE.

WILLARD IRVING TWOMBLY, OF NEW YORK, N. Y.

DESIGN FOR A VEHICLE-BODY.

48,299.

Specification for Design. Patented Dec. 14, 1915.

Application filed September 21, 1914. Serial No. 862,815. Term of patent 7 years.

To all whom it may concern:

Be it known that I, WILLARD IRVING TWOMBLY, a citizen of the United States, residing in the borough of Manhattan, in the city, county, and State of New York, have invented a new, original, and ornamental Design for Vehicle-Bodies, of which the following is a specification.

This invention relates to the design of a vehicle body, and relates particularly to the design of a body for motor vehicles having a narrow tread, such for instance, as are known as "cycle cars", and it is the object of the invention to provide a design of a body for a vehicle of this type which is useful, ornamental and enhancing in appearance.

In the drawing, Figure 1 is a perspective view of the vehicle body. Fig. 2 is a plan view. Fig. 3 is a view looking at the front; and Fig. 4 is a view looking at the back.

As shown in the drawing the essential feature of my design is to provide a body having two seats 5 and 6, one forward of the

other, the rear seat 6 being adapted for two persons seated side by side and the forward seat located centrally of the body and adapted for one person only. The sides 7, 8 of the body converge toward each other or incline inwardly toward the front whereby the forward end of the body is of less width than the rear, and the sides converge or curve inwardly from the top to the bottom so that the bottom of the vehicle is of less width than the top. The body is divided by a transverse partition 9 into two compartments, the rear seat 6 being located in one compartment, and said compartment having a door 10 to permit of easy entrance to and exit therefrom, and the seat 5 being located in the other compartment.

I claim:

The ornamental design for a vehicle body substantially as shown and described.

WILLARD IRVING TWOMBLY.
